(57) **CLAIM**

The ornamental design for a cornhole board, as shown and described.

DESCRIPTION

FIG. 1 is a perspective view of a cornhole board, showing my new design;

FIG. 2 is another perspective view thereof;

FIG. 3 is a front elevational view thereof, the rear elevational view being a mirror image of FIG. 3;

FIG. 4 is a left elevational view thereof;

FIG. 5 is a right elevational view thereof;

FIG. 6 is a top plan view thereof;

FIG. 7 is a bottom plan view thereof;

FIG. 8 is a partial enlarged view of FIG. 1;

FIG. 9 is a partial enlarged view of FIG. 1;

FIG. 10 is a partial enlarged view of FIG. 1;

FIG. 11 is a partial enlarged view of FIG. 1;

FIG. 12 is a partial enlarged view of FIG. 1;

FIG. 13 is a partial enlarged view of FIG. 1;

FIG. 14 is a partial enlarged view of FIG. 1;

FIG. 15 is a partial enlarged view of FIG. 1;

FIG. 16 is a partial enlarged view of FIG. 1;

FIG. 17 is a partial enlarged view of FIG. 1;

FIG. 18 is a partial enlarged view of FIG. 2;

FIG. 19 is a partial enlarged view of FIG. 2;

FIG. 20 is a partial enlarged view of FIG. 2;

FIG. 21 is a partial enlarged view of FIG. 2;

FIG. 22 is a partial enlarged view of FIG. 2;

FIG. 23 is a partial enlarged view of FIG. 2;

FIG. 24 is a partial enlarged view of FIG. 2;

FIG. 25 is a partial enlarged view of FIG. 2;

FIG. 26 is a partial enlarged view of FIG. 2;

FIG. 27 is a partial enlarged view of FIG. 6;

FIG. 28 is a partial enlarged view of FIG. 6; and,

FIG. 29 is a partial enlarged view of FIG. 7.
